Patented Sept. 30, 1975

237,018

FLEXIBLE CONTAINER FOR MEDICAL FLUIDS

Harold Anthony Betka and Albert Frank Bujan, Waukegan, Ill., assignors to Abbott Laboratories, North Chicago, Ill.

Filed Dec. 10, 1973, Ser. No. 423,323

Term of patent 14 years

Int. Cl. D24—04

U.S. Cl. D83—1 U

FIG. 1 is a perspective view of a flexible container for medical fluids showing our new design;

FIG. 2 is a side elevational view;

FIG. 3 is a front elevational view;

FIG. 4 is a top plan view; and

FIG. 5 is a bottom plan view.

We claim:

The ornamental design for a flexible container for medical fluids, substantially as shown and described.
